UNITED STATES PATENT OFFICE.

WILLIAM ZAPIS, OF JERSEY CITY, NEW JERSEY.

SHOE LACING.

Application filed June 14, 1922, Serial No. 568,105. Renewed September 6, 1923.

To all whom it may concern:

Be it known that I, WILLIAM ZAPIS, a subject of the King of Greece, residing at 25 Montgomery Street, Jersey City, in the 5 county of Hudson and State of New Jersey, have invented new and useful Improvements in Shoe Lacings, of which the following is a specification.

My present invention relates to a novel 10 and useful type of shoe-lacing, and has for its object a lacing which will be more readily, quickly and smoothly operated than the forms commonly in use, and in which shorter laces and a smaller number of eyelets 15 may be used.

A further object of the invention as embodied in this lacing arrangement is to provide a shoe that is more comfortable upon the feet, and in which the shape of the edge 20 of the shoe of the lacing is maintained and the customary buckling avoided.

In accomplishing these objects, I provide a construction in which the eyelets are placed very close to the edges of the shoe, 25 and the edges of the shoe are suitably reinforced, so that the shape is maintained, and but a small amount of lace is held between the shoe and the foot when the shoe is laced, making the shoe more comfortable to wear.

My invention consists in the construction, combination and arrangement of parts herein described and claimed, and illustrated in the accompanying drawings.

35 In these drawings, in which I have illustrated a preferred embodiment of my invention as applied to a high shoe, (although it is equally applicable to a low shoe):

Figure 1 is a perspective view of a shoe 40 having the improved fastening device applied thereto;

Figure 2 is a detail sectional view approximately on the line 2—2 of Fig. 1, showing the manner of application of the invention 45 to a shoe; and

Figure 3 is a perspective view of one of the reinforcing and shape-retaining members.

Similar characters of reference indicate 50 corresponding parts throughout all figures of the drawings.

Referring to these drawings, I make use of a shoe 1 of ordinary construction having the edges of the upper at the lacing parts 55 spaced perhaps a little more widely from

each other than in the ordinary construction. At each of these lacing edges I provide what I have termed "loops" 5. The loops 5 may be formed by securing to each of the lacing edges a strip of leather 2 folded as at 3, and preferably secured either to overlap the edge of the shoe 1, or placed within the edge of the shoe and between the leather of the shoe and the leather of the lining, the folded edge 3 of the strip 2 being provided with a number of cut-away portions 4, leaving remaining between these points portions 5, which comprise the said loops. These loops are provided at each point that it is desired to place eyelets 6 for receiving the lace 11.

The members 2 are secured to the edge of the shoe 1 preferably by stitching. This stitching may, of course, be along the outer edge 9 of the member 2 and also along the 75 inner edge, being curved out as at 10 around each eyelet, but otherwise following closely the edge of the shoe.

Within each of the loops 5 there is inserted a stiffening member, such as a piece 80 of wire 7, which may preferably have its surface roughened as at 8 in order to furnish a substantial grip within the loop 5 and retain the wire in place. The eyelet 6 is stamped into place in the loop member 85 closely adjacent to the wire stiffening member, being thus as near to the edge of the shoe as possible, and yet reinforced by the wire member so that there is no danger of tearing the eyelet 6 out of the leather. 90

Due to these stiffening members 7 adjacent to the eyelets, the number of eyelets required is greatly reduced, perhaps fifty per cent, six pairs sufficing as shown in the drawing instead of the usual ten or twelve pairs. These stiffening members further perform the service of maintaining the edge of the shoe comparatively straight and avoiding the buckling that often occurs between the eyelets in the ordinary laced shoe. 100

Furthermore, because of the proximity of the eyelets to the edge of the shoe, there is but a very small amount of lacing passing under the shoe from the edge to the eyelet, and pressing into the foot of the wearer; and the shoe is consequently more comfortable to wear, in addition to being more attractive in appearance.

By reason of the reduction in the number of eyelets, and also their particular ar- 110

rangement and the assistance afforded by the reinforcing strips or members; the shoe is much easier to lace and unlace in putting it on and taking it off than the ordinary 5 shoe. When the shoe has been put on the foot, it is only necessary to pull on the ends of the laces before tying, so smoothly does the arrangement work; and after untying, the upper can be spread apart without loosening the laces by hand, the laces being thus 10 loosened to permit removal of the shoe.

Having now described my invention, I claim and desire to secure by Letters Patent:

15 1. In a shoe lacing arrangement, the combination comprising a strip of leather folded and secured to each lacing edge of a shoe, the folded portion being cut at intervals to form loops; reinforcing and shape-retaining 20 members disposed in said loops; and eyelets

secured in said loop members closely adjacent said reinforcing members.

2. In a shoe lacing arrangement, the combination comprising a strip of leather folded and secured to each lacing edge of a shoe, 25 the folded portion being cut at intervals to form loops; roughened wire members disposed in said loops; and eyelets secured in said loop members closely adjacent said wire members.

3. In a shoe lacing arrangement, the combination comprising loops formed adjacent each lacing edge of a shoe; reinforcing and shape-retaining members disposed in said loops; and eyelets secured in said loop members closely adjacent said reinforcing members.

In testimony whereof I have signed my name to this specification.

WILLIAM ZAPIS
